[57] ABSTRACT

An amusement device is formed as a unitary moulded body of plastics material and is designed so that it can be gripped generally between the knees of a player while he walks or otherwise ambulates and attempts to prevent a ball rolling out of an open-ended groove formed in the top surface of the device. An alternative embodiment of the device is adapted to be held between the knees of two players.

AMUSEMENT DEVICE

BACKGROUND OF THE INVENTION

The present invention relates generally to amusement devices and more particularly to a device which is intended to be gripped essentially between the knees of a person while such a person attempts to walk or otherwise ambulate while attempting to prevent a ball rolling from such a device.

There have heretofore been suggested numerous devices which, in use, require a person to acquire the ability to make somewhat unusual and potentially humorous contortions. Some of the previously known devices required a person to adopt somewhat humorous positions for balancing purposes while other devices have demanded relatively rapid movement of the player's body for the purpose of maintaining a device in motion.

It is an object of this invention to provide an amusement device which calls for a certain degree of acquired skill and/or co-ordination on the part of a user while providing amusement both to the player himself and to any onlookers.

Another object of this invention is to provide an amusement device for the aforesaid purpose and which device can be manufactured at an extremely low cost and which can, therefore, be sold at a relatively low price.

Yet another object of this invention is to provide an amusement device which can be manufactured so that it can be used by one person alone or, in a different form, jointly by two persons, as desired.

Other objects of the invention will become apparent as the description herein proceeds.

SUMMARY OF THE INVENTION

Broadly, the present invention provides an amusement device comprising a body having a top surface and in turn including a central portion and first and second end portions at opposite ends of said central portion, each said end portion being contoured so that said device can be gripped generally between a person's knees with said top surface thereof facing upwardly and a track having at least two open ends being formed in said body downwardly of said top surface thereof for receiving a ball, whereby said device can be gripped generally between a person's knees and a ball can be disposed in said track to provide amusement as such person attempts to ambulate while attempting to prevent the ball rolling out of said track through an open end thereof.

When an amusement device in accordance with this invention is intended jointly to be used by two players, such a device is formed with two transversely separated pair of end portions whereby such a device can be gripped generally between the knees of two players with the top surface of the device facing upwardly.

Other features and various advantages of the amusement devices of this invention will become apparent as the description herein proceeds.

BRIEF DESCRIPTION OF THE DRAWINGS

The invention will now be described merely by way of illustration with reference to the accompanying drawings in which:

FIG. 1 is a perspective view of one embodiment of an amusement device in accordance with this invention;

FIG. 2 is a view showing the manner in which the amusement device of FIG. 1 is gripped generally between the knees of a person;

FIG. 3 is a vertical section through the device shown in FIG. 1 when taken as indicated by the arrows 3-3 of FIG. 1; and

FIG. 4 is a perspective view of another embodiment 10 of a device in accordance with this invention and illustrating the manner in which that particular device is used.

DESCRIPTION OF THE PREFERRED EMBODIMENTS

Referring first to FIGS. 1 to 3 of the accompanying drawings, there is shown therein generally at 10 one embodiment of an amusement device in accordance with this invention. The device 10 is in the form of an integrally moulded body of a plastic material such as polyethylene.

The body of the device 10 includes a central portion generally indicated at 10a and two essentially bifurcated end portions integrally formed with the central portion 10a. The first end portion includes limbs 11 and 12 while the second end portion includes limbs 13 and 14. The limbs 11 and 12 diverge outwardly from one end of the central portion 10a while the limbs 13 and 14 similarly diverge outwardly from the other end 30 of the central portion 10a, the limbs 12 and 14 extending forwardly and the limbs 11 and 13 extending rearwardly.

The limbs 11 and 12 at one end of the device 10 define therebetween a generally concave surface 16 while the limbs 13 and 14 at the other end of the device 10 define therebetween a concave surface 17.

The body of the device 10 is formed in its top surface 20 with a track generally indicated at 21 which includes an essentially straight portion 22 extending along the central portion 10a and limb tracks 23, 24, 25 and 26 extending along respective ones of the limbs 11, 12, 13 and 14. Each of the tracks 23, 24, 25 and 26 communicates with the central track 22 and is open-ended at the end of a respective one of the limbs 11, 12, 13 and 14 as will readily be understood by reference to FIG. 1.

Referring now in greater detail to FIG. 3 of the accompanying drawings, it will be seen that the device 10 is shown therein as being formed as a hollow and integrally moulded structure of a plastics material such as polyethylene. A device such as that indicated at 10 can, however, be formed of any appropriate material but the use of an inexpensive material such as polyethylene is particularly indicated.

Referring to FIG. 2, the manner in which the device 10 is intended to be used will now be briefly explained. The device 10 is intended to be gripped generally between a person's knees, as shown, and a small ball, for example, a ball bearing of appropriate diameter 27, is placed in the central track 22, considerable amusement and jollification then being provided when the person attempts to walk or otherwise ambulate with the device so gripped generally between his knees while, at the same time, attempting to prevent the ball rolling out of the track 21.

In accordance with another useful but optional feature of this invention, the device 10 is formed with the configuration of a stylized bone as actually illustrated

in FIGS. 1 and 2. It should, however, be understood that it is equally within the scope of this invention to provide a device having a completely different appearance.

The alternative embodiment of an amusement device in accordance with this invention as indicated generally at 30 in FIG. 4 has many features in common with the device 10 hereinbefore specifically described. The device 30 is, however, intended to be used by two persons as shown in FIG. 4 rather than by a single person as illustrated in FIG. 2 for the device 10.

The device 30 also has the general configuration of a stylized bone and is formed as a unitary moulded structure of a suitable plastics material. The device 30 includes a central portion generally indicated at 31 and which in turn includes a transversely extending spine 32 and cross heads 33 and 34. Each of the cross heads 33 and 34 terminates in two bifurcated end portions, each including two limbs which define therebetween a generally concave surface intended to be engaged generally by a respective knee of one of the players. For example, the cross head 33 terminates in bifurcated ends including limbs 35, 36 and 37, 38 while the cross head 34 terminates in bifurcated ends including limbs 39, 40 and 41, 42. The limbs 35, 36 together define a 25 concave surface 44 and the limbs 37, 38 define a concave surface 45, the surfaces 44 and 45 being gripped in the use of the device 30 essentially between the knees of one of the two players. A second person then holds the device 30 essentially by gripping it between his knees with generally concave surfaces 46 and 47 defined by the limbs 39, 40 and 41, 42 respectively between his knees.

A groove 50 is formed in the top surface of the spine 32 and the groove 50 opens at its ends into grooves 51 and 52 formed in the cross heads 33 and 34 respectively. At their ends, the grooves 51 and 52 open into individual and open-ended grooves provided in the individual limbs at the ends of those cross heads. For example, the groove 51 in the cross head 33 opens into grooves 53 and 54 extending along the limbs 35 and 36 respectively as well as into grooves 55 and 56 extending along the limbs 37 and 38 respectively. Similarly, the groove 52 in the cross head 34 opens at one end into grooves 57 and 58 extending along the limbs 39 and 40 respectively and, at its other end, into grooves 59 and 60 extending along the limbs 41 and 42 respectively.

In use, a small ball is placed in the groove 50 and the two players attempt to walk or otherwise ambulate without allowing the ball to roll out of the ends of the 50 grooves.

For convenience, a ball-receiving recess 64 can be provided as shown in FIG. 1 in a device in accordance with this invention for accommodating the ball when the device is not in use. The ball may be disposed in such a recess and retained therein by means of a simple rubber plug 65 or simply by means of a piece of adhesive tape placed over the open end of such a recess.

Although the invention has been specifically described with reference to the particular embodiments thereof as shown in the accompanying drawings, it will be understood that numerous variations and modifications are possible without departing from the scope of the invention. For example and as already indicated, a device in accordance with this invention need not be formed with the configuration of a stylized bone as actually illustrated. Nor, is it essential that such a device

be formed of a plastics material, the use of other materials being equally possible although generally not economically attractive.

What is claimed is:

5 1. An amusement device comprising (a) a body having an outer surface in turn comprising a top surface and said body comprising a longitudinally extending central portion and first and second end portions at opposite longitudinal ends of said central portion and integral therewith, said end portions having essentially bifurcated structures and each comprising mutually diverging first and second limbs so to define therebetween generally concave end surfaces facing in opposite directions, a track having at least two open ends 10 being formed in said body downwardly of said top surface thereof with said track opening through said outer surface of said body below said top surface thereof, and (b) a ball disposed in said track for rolling movement therealong, whereby said device can be gripped generally between a person's knees with said top surface thereof facing upwardly to provide amusement as such a person attempts to ambulate while simultaneously attempting to prevent the ball rolling out of said track through a said open end thereof.

2. An amusement device as claimed in claim 1 and in which said track is formed with at least one said open end in each of said first and second end portions.

3. An amusement device as claimed in claim 1 and in which said track comprises a central track portion formed in said central portion of said body and extending generally longitudinally therealong and first and second open-ended track portions in each of said end portions of said body, each of said first and second track portions in each of said end portions opening into said central track portion terminally thereof.

4. An amusement device as claimed in claim 3 and in which said track comprises an upwardly open groove.

5. An amusement device as claimed in claim 3 and in which said first and second track portions in each said end portion of said body extend along respective ones of said first and second limbs of that end portion.

6. An amusement device as claimed in claim 5 in which said body is formed as a unitary moulded structure of a plastics material.

7. An amusement device as claimed in claim 1 and in which said body comprises two said central portions with said end portions and which central portions are interconnected by and integrally formed with a transversely extending bridge portion so that said device can be gripped generally between the knees of two persons.

8. An amusement device as claimed in claim 7 in which said track comprises a bridge track portion which extends along said bridge portion, two central track portions extending along respective ones of said central portions and first and second open-ended track portions in each of said end portions, said central track portions opening into said bridge track portion terminally thereof and said first and second track portions in each of said end portions opening into respective ones of said central track portions terminally thereof.

9. An amusement device as claimed in claim 8 and in which said track comprises an upwardly open groove.

10. An amusement device as claimed in claim 9 in which said body is formed as a unitary moulded structure of a plastics material.
